(57) **CLAIM**

I claim the ornamental design for an automotive grille, as shown and described.

DESCRIPTION

FIG. 1 is a top, front and left side perspective view of an automotive grille showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof; and,
 FIG. 7 is a bottom plan view thereof.

The portions of the automotive grille shown in broken lines are for illustrative and environmental purposes that form no part of the claimed design.
